UNITED STATES PATENT OFFICE.

JOHN H. COVEY, OF BUFFALO, NEW YORK, ASSIGNOR OF ONE-HALF TO WILLARD KELLS, OF BUFFALO, NEW YORK.

DERAILING-SWITCH.

No. 892,136.

Specification of Letters Patent.

Patented June 30, 1908.

Application filed September 20, 1907. Serial No. 393,758.

To all whom it may concern:

Be it known that I, JOHN H. COVEY, a citizen of the United States, residing at Buffalo, in the county of Erie and State of New York, have invented a new and useful Improvement 5 in Derailing-Switches, of which the following is a specification.

This invention relates to a derailing switch which is applied to a rail of railway tracks 10 for throwing the cars or train off the rails when the derailing switch has been set for this purpose.

The object of this invention is to provide a switch of this character which is simple in 15 construction and reliable in operation and which is not liable to be interfered with by parts depending from the car nor liable to become clogged by snow and ice.

In the accompanying drawing: Figure 1 is 20 a top plan view of my improved derailing switch, showing the same in its operative position on a rail. Fig. 2 is a cross section thereof in line 2—2, Fig. 1. Fig. 3 is a longitudinal section thereof in line 3—3, Fig. 2. 25 Fig. 4 is a perspective view of the derailing lever and block. Fig. 5 is a similar view of the support or bracket whereby the derailing lever is pivotally mounted on the rail.

Similar letters of reference indicate corresponding parts throughout the several views.

A represents one of the rails of a railway track which may be of any well known or approved construction and supported upon ties *a* in the usual manner.

B represents the derailing block or shoe which may rest upon the top of the rail so as to be engaged by the wheel of a car and run the latter off the track when this is desired and which may be moved laterally and 40 downwardly on one side of the rail so as to leave the top of the rail clear and also avoid projecting the block upwardly above the top of the rail so as to prevent interference with any parts depending from the car. This 45 block is shown in its operative position by full lines in Figs. 1, 2 and 3 and by dotted lines in Figs. 1 and 2. The derailing block may be variously constructed but preferably consists of a body *b* adapted to rest lengthwise upon the top of the rail and having its front end inclined, whereby the tread of the car wheel is guided gradually from the rail to the block and an oblique deflecting flange or rib *b*¹ is arranged on the rear part of the body 55 and extending from a point inside of the rail

toward the outer side thereof so as to be engaged by the flange of the wheel and thereby operate to move the wheel gradually laterally off the rail.

The derailing block is mounted on the upper arm *C* of an elbow-shaped derailing lever the other or lower arm *C*¹ of which is connected by any suitable means with the operating mechanism of an adjacent switch stand or semaphore or with any other suitable operating mechanism. That portion of the operating mechanism for the derailing lever and block shown in the drawings consists of a horizontally turning elbow lever *D* pivoted adjacent to the rail and having one 60 of its arms connected by a rod or link *d* with the lower arm of the derailing lever while its other arm is connected by a rod or link *d*¹ with the device whereby the derailing switch is operated.

Various means may be provided for imparting a combined sliding and pivotal movement to the derailing lever for shifting the block thereof into and out of its operative position. The preferred means for this purpose shown in the drawings consists of a pair of guide pins *e*, *e* arranged on opposite sides of the central part of the derailing lever and entering curved slots, grooves or guide-ways *f*, *f* formed on the inner sides of guide lugs *F*, *F* which are arranged on opposite sides of the derailing lever. These guide lugs are arranged on a longitudinal supporting plate *G* which is secured vertically to the adjacent outer side of the web of the rail by means of 90 bolts *g*, as shown in Fig. 3, or by any other suitable fastener. The curvature of the guideways or grooves extends generally in a vertical direction and the inner side of the same is nearest to the rail and the upper ends 95 of these grooves terminate below the top of the rail while the lower ends thereof terminate below the underside of the rail. By this construction of these grooves any outward pull on the lower arm of the derailing lever causes 100 the latter to slide with its guide pins upwardly in the guide-ways or grooves on a curved line and also turn with its pins in these grooves so that the upper arm of the lever is raised and also swung inwardly and downwardly for 105 bringing the derailing block squarely on top of the rail, as shown by full lines in Fig. 2. Upon pushing the lower arm of the derailing lever inwardly the same will slide with its guide pins downwardly in the guide-ways or 110

grooves and at the same time turn in a vertical plane so as to bring the lower arm thereof underneath the track and its upper arm together with the derailing block mounted thereon into a position along the outer side of the rail and below the top of the latter, as shown by dotted lines in Fig. 2. By this combined pivotal and sliding connection of the derailing lever with its support or bracket, a very compact and strong construction is produced while at the same time a range of movement of considerable length is obtained for permitting the derailing block to be shifted into its proper position over the rail when it is required for use and also to be shifted laterally and downwardly on the outer side of the rail where it will be out of the way and not form an obstruction which would be liable to interfere with parts depending from the car.

The outer side *h* of the guide lugs form closures for the outer sides of the guide-ways or grooves therein and thus prevent snow and ice from entering these grooves at the outer sides and thereby reduce the liability of interference by ice and snow with the free movement of the guide pins in these guide-ways or grooves. The downward movement of the derailing lever is limited by its guide pins engaging with the lower ends of the guide-ways or grooves on the bracket but the upward movement thereof is preferably limited by means of a stop or stop lug *i* projecting inwardly from the central part of the derailing lever and engaging with the underside of a laterally projecting stop or stop flange *j* arranged on the upper portion of the supporting plate, as shown by full lines in Fig. 2. By this means the downward pressure of the wheel which is exerted upon the inner portion of the derailing block when engaged by the car wheel is resisted by the stop lug *i* on the derailing lever engaging with the stop flange *j*, thereby relieving the guide pins from this strain and preventing the same from becoming broken.

Between the derailing block and the guide pins the upper arm of the derailing lever is provided with an inwardly projecting thrust lug *k* which is substantially V-shaped and fits into the correspondingly shaped recess formed between the outer side of the rail head and the upper side of the stop flange *j* on the supporting bracket, as shown in Fig. 2. By this means the derailing lever and bracket are interlocked in the operative position of the lever and block, whereby the lateral outward thrust of the car wheel against the block and lever upon engaging the same is prevented from displacing or shifting the lever and block out of their operative position, thereby insuring the retention of these parts in position so as to operate reliably in derailing the car.

For the sake of simplicity, cheapness and

durability the derailing lever, guide pins and block are preferably formed integrally. For the same reason the supporting plate, guide lugs and stop flange which constitute the supporting bracket of the lever are also formed in one piece. In order to permit of assembling or dismembering the derailing lever and connecting parts with the bracket when thus constructed passage-ways or notches *l* are formed in the inner walls of the guide-ways or grooves above the lower ends of the same, as shown in Figs. 2, 3 and 5. Through these notches the pins of the derailing lever may be moved inwardly and outwardly for assembling or dismembering the lever and bracket when the latter is detached from the rail. But when the bracket is attached to the rail these notches or passageways are closed by the adjacent base portion of the rail, thereby preventing the guide pins from passing out through the same and dismembering the parts of the derailing switch when the same is installed and in condition for use.

My improved derailing switch is very strong and compact, the same when not in use does not form a dangerous obstruction above the level of the track, and owing to the combined sliding and pivotal movement of the lever in a curved path the parts are not liable to be interfered with by snow and ice, thus reducing the liability of impairing the switch to a minimum.

I claim as my invention:

1. A derailing device comprising a supporting bracket, a derailing piece, and a single connection between said derailing piece and bracket constructed to permit of a combined pivotal and sliding movement of the derailing piece relatively to said bracket for moving the derailing piece into its operative and inoperative position.

2. A derailing switch comprising a support having a pair of lugs which are provided with guide-ways extending in a vertical direction, a lever arranged between said lugs and having pins moving in said guide-ways, and a derailing block arranged on said lever, substantially as set forth.

3. A derailing switch comprising a support having a pair of lugs which are provided with guide-ways extending in a vertical direction, a lever arranged between said lugs and having pins moving in said guide-ways, and a derailing block arranged on said lever, the inner walls of said ways having notches through which said pins are adapted to pass in assembling or dismembering the parts, substantially as set forth.

4. A derailing switch comprising a support having a pair of lugs which are provided with guide-ways extending in a vertical direction, a lever arranged between said lugs and having pins moving in said guide-ways, and a derailing block arranged on said lever, the inner walls of said ways having notches

- through which said pins are adapted to pass in assembling or dismembering the parts and which are adapted to be closed by the rail of a track when in use, substantially as set forth.
- 5 5. A derailing switch comprising a support having a pair of lugs which are provided with guide-ways extending in a vertical direction, a lever arranged between said lugs and having pins moving in said guide-ways, a derailing block arranged on said lever, and a stop arranged on said lever and adapted to engage with a stop on the support for limiting the upward movement of the lever, substantially as set forth.
- 10 15. 6. A derailing switch comprising a support having a pair of lugs which are provided with guide-ways extending in a vertical direction, a lever arranged between said lugs and having pins moving in said guide-ways, a derailing block arranged on said lever, a stop arranged on the inner side of said lever, and a stop arranged on said support between its lugs and adapted to be engaged by the stop on the lever, substantially as set forth.
- 20 25. 7. A derailing switch comprising a support having a pair of lugs provided on their inner sides with guide-ways and a stop flange between the upper parts of said lugs and forming a recess between said stop flange and the head of the rail when the support is attached to the same, a lever arranged between said lugs and provided on its upper arm with a derailing block and on its opposite sides with pins moving in said guide-ways, and a lug
- arranged on the upper arm of said lever and 35 adapted to fit in said recess, substantially as set forth.
8. A derailing switch comprising a bracket or support composed of a plate adapted to be attached to one side of the web of a rail, two lugs projecting laterally from the side of the plate and provided on their opposing inner sides with upwardly extending curved guide-ways or grooves, and a stop flange arranged on the upper part of said plate between said 40 lugs, a lever arranged between said lugs and provided on opposite sides with pins which move in said guide-ways, a derailing block arranged on the upper arm of said lever and adapted to rest on said rail, a stop lug arranged on the inner side of the central part of said lever and adapted to engage with the under side of said stop flange, and a thrust lug arranged on the inner side of the upper arm of said lever and adapted to engage with 45 the upper side of said stop flange, the inner walls of said guide-ways having notches which are adapted to be closed by the base of the rail and through which the pins of the lever are adapted to pass in assembling or 50 dismembering the parts, substantially as set forth.
- 55 Witness my hand this 16th day of September, 1907.
